MULTIHOLE PUNCH

John Allan Carpenter, Waban, Newton, Mass.

Application January 16, 1946, Serial No. 641,529

10 Claims. (Cl. 164—91)

1

This invention relates to a punch particularly adapted for use as a paper punch.

The invention has for an object to provide a novel and superior construction of punch and particularly of a multi-hole punch of novel and improved construction wherein the one or more punch units are mounted to be capable of being adjustably moved longitudinally to adjustably locate the punch unit or units at different and predetermined distances from an edge of the paper sheet or sheets to be punched, and also with relation to one another to provide desired hole spacings in the paper being punched.

With this general object in view, and such others as may hereinafter appear, the invention consists in the punch and in the various structures, arrangements and combinations of parts hereinafter described and particularly defined in the claims at the end of this specification.

In the drawings, illustrating the preferred embodiment of the invention, Fig. 1 is a plan view of a multi-hole punch embodying the present invention, a portion thereof being broken away to show an individual punch unit; Fig. 2 is a front elevation with a portion broken away and with an individual punch unit shown in cross section; Fig. 3 is an end view showing the punch in its depressed or operating position; Fig. 4 is a view in cross section taken on the line 4—4 of Fig. 1; Fig. 5 is a side elevation of an individual punch unit; Fig. 6 is a view in cross section taken on the line 6—6 of Fig. 5; Fig. 7 is a detail view of a friction element for maintaining the punch unit in its adjusted position as viewed from the right in Fig. 5; and Figs. 8 and 9 are plan views of the present multi-hole punch showing the punch units adjusted for different hole spacings in the paper to be punched.

In general, the present invention contemplates a novel, efficient and durable punch having one or more individual punch units mounted to be capable of being adjustably moved into different positions to punch one and preferably a plurality of holes in desired relation both to one another and to the edge of the sheet or sheets to prepare such sheets to be inserted in or incorporated with a loose-leaf ring binder. The multi-unit punch may also be adjusted to punch but one hole at a predetermined distance from one edge of the sheet to be punched.

In its preferred form, the invention is embodied in a multi-hole punch of the type in which an operating lever or presser bar is mounted to be rocked in a direction toward the rear of the punch and away from the front or paper receiv-

2

ing end of the punch whereby the punching operation may be easily and conveniently performed while the punch is held in the hand, the individual units being arranged to be operated simultaneously by the presser bar.

The multi-hole punch preferably includes a base member in which the individual punch units are adjustably mounted, and each punch unit is provided with an individual presser arm arranged to cooperate with the main presser bar to permit adjustment of the units lengthwise of the presser bar and to effect positive operation of all the punch members upon rocking movement of the main presser bar. The construction of the individual punch units imparts maximum rigidity with relatively light weight parts, each unit being capable of performing an individual punching operation, and also capable of being adjustably mounted with similar units in a multi-hole punch for simultaneous operation.

The present construction of punch also provides maximum visibility and accessibility for introducing the paper into the punch and for adjusting the individual punch units to the spacing required.

Referring now to the drawings, the present multi-hole punch comprises in general, a base member 10 upon which at least one and preferably a plurality of individual punch units 12 are mounted to be capable of being adjustably moved longitudinally of the base member 10. An actuating member or presser bar 14 also mounted upon the base member is arranged to operate all of the punch units simultaneously. Each individual punch unit 12 includes a punch member 16 slidably supported for vertical reciprocation in a supporting bracket 18, and a punch plate 20 secured to and supported by the bracket 18, each punch plate being provided with an opening 21 with which the punch member 16 is arranged to cooperate to punch out a hole in one or more sheets of paper 22 inserted between the punch and the punch plate.

The punch supporting bracket 18 is constructed and designed to impart maximum rigidity to its individual punching unit and may be made of relatively light weight metal. As herein shown each supporting bracket 18 may and preferably will be formed from one piece of metal bent to provide an upper wall 24, depending side walls 26, 28 and a base formed by bent-in portions 30, 32 of the side walls 26, 28 respectively, thus forming a structure substantially rectangular in cross section, as shown in Fig. 6. The punch member 55 16 is slidably supported in the upper wall 24 and

in an intermediate wall 34 joined to the upper wall by a depending vertical wall 36 formed by bending a portion of the upper wall 24 downwardly and inwardly as clearly shown in Fig. 4.

The punch plate 20 is arranged to form an integral part of the supporting bracket 18 and, as herein illustrated, comprises a base portion 38 and a punch cooperating portion 40 joined by an angular bent portion 42. The plate 20 is formed to fit over the lower portion of the supporting bracket 18, the punch cooperating plate 40 being arranged to fit into a slot comprising the paper receiving slot 44 formed in the side walls 26, 28. With this construction, the underside of the punch plate portion 40 bears against the exposed edges of the side walls 26, 28 as illustrated in Fig. 6, the latter forming a firm and rigid support for the punch plate for cooperation with the punch member during the punching operation. The base portion 38 fits under the bottom wall of the supporting bracket 18 and may be spot-welded or otherwise secured thereto to form an integral part of the supporting bracket 18.

As herein shown, each punch unit is provided with a presser arm 46 pivotally mounted on a pin 48 supported between forwardly extended arms 50 of the side walls 26, 28. The punch member 16 is connected to the presser arm 46 by a pin 52 which extends horizontally through the upper end of the punch member 16 and into elongated slots 54 formed in the depending side walls of the presser arm. A spring 56 coiled about the pivot pin 48 is arranged to normally urge the arm 46 and the punch member 16 upwardly as shown in Fig. 4 the spring having one end bearing against the underside of the arm 46 and its other end bearing against the intermediate wall 34 of the supporting bracket 18. The punch member 16 is provided with a shouldered portion 58 which bears against the underside of the upper wall 24 to limit the movement of the punch member upwardly. Upon downward pressure against the arm 46 the punch member is moved downwardly into cooperative engagement with the punch plate by contact of the arm with the top of the plunger. The pin 52 is slidably received in the slots 54 permitting freedom of movement of the punch member vertically during the rocking of the arm 46, and also providing a positive connection for raising the punch member in the event a jam should occur such as to render the spring 56 inoperative to return the punch member to its raised position. The base portions of each individual unit are provided with openings 60 in alignment with the punch member 16 for assembly purposes, to permit the punch member to be inserted through the bottom of the unit.

The elongated base member 10 in which the individual punch units are received comprises a flat plate having upturned edges to form a curved forward wall 62, a rear wall 64 and end walls 66, 68. The punch units are mounted in the base to be capable of movement lengthwise of the base, so that the one or more punch units may be adjustably positioned at any desired distance from either end of the base to locate the punched holes in the paper sheets 22 at predetermined distances from the edge, and also the distance between the several punch units may be adjustably determined to selectively space the punched holes from one another. The forward portion of each punch unit is extended under the curved forward wall 62 and the opposite end of each unit extends substantially to the rear wall 64 of the base, as

shown in Fig. 4. The individual punch units 12 are further guided for longitudinal adjustment in the base member 10 by the provision of a guide rod 70 which extends lengthwise of the base between the end walls 66, 68 the rod being detachably connected to the end walls by screws 72 for assembly purposes. As herein shown, the rod 70 extends through openings in the side walls 26, 28 of the supporting bracket 18, the punch units being slidably mounted thereon. Provision is made for frictionally retaining the units in their adjusted positions and as herein shown a friction element 74 carried by each unit 12 and engageable with the rod 70 is provided for this purpose. The spring friction member as best shown in Fig. 7 is formed by bending a sheet of metal in a substantially U-shaped form, the arms of the U being provided with openings 76 therethrough which the rod extends. The arms of the U extend between and engage the inner walls of the supporting bracket 18 and one arm of the U is extended and curved, as shown, to yieldingly bear against the rod 70 and in frictional engagement therewith. With this construction it will be seen that the individual units may be moved lengthwise of the base 10 to dispose the units in spaced relation and that the units are held in their adjusted position by the action of the friction element.

The presser bar 14 for actuating the individual punch units 12, as herein shown, comprises an elongated handle portion having forwardly extended arms at 78 at either end formed integrally with the handle portion. The bar is pivotally mounted on pins 80 supported in the end walls 66, 68 of the base member 10. As best shown in Fig. 4, the handle portion of the presser bar 14 is preferably formed to provide a socket 82 at the outer end thereof defined by an upper wall 84 and a relatively short lower wall 86 formed by bending over the end of the upper wall as shown. The socket 82 is arranged to receive the upper ends of the presser arms 46 of the punch units 12. The pivot pins 80 of the presser bar 14 may and preferably will be arranged in substantial alignment with the pivot pins 48 of the individual units 12.

As herein shown, the forward portion of the presser arm 46 of each unit is enclosed by a wall 88, the remainder of the arm comprising extensions 90 of the side walls of the arm which are received in the socket 82. With this construction, the upper wall 88 of each presser arm is arranged substantially flush with the upper wall 84 of the presser bar 14. The extensions 90 of the arms 46 are loosely or slidably received in the socket 82 of the presser bar to permit lengthwise adjustment of the punch units therein and relative sliding movement of the arms 46 upon rocking of the presser bar 14 during the punching operation.

It will be observed that the above described structure of the presser bar 14 provides a relatively large open space 92 between the arms 78 and the edge of the upper wall 84 at the front or paper receiving end of the unit thus providing access to the punch units 12 for adjusting the same, and also providing maximum visibility for introducing the sheets of paper to be punched.

In the operation of the device, the forward edges of a group of sheets to be punched are presented against a stop 93 formed by the end of the paper receiving slot 44 of the individual punch members 12 and the adjacent side edges of the group are presented against the left end wall

of the base member 10. As illustrated in Fig. 2, the end walls 66, 68 may be reinforced by metal plates 94, 96 and which may be spot-welded or otherwise secured thereto, the end wall reinforcing member 94 forming the end stop for the sheets of paper to be punched. Thereupon, rocking of the presser bar 14 will effect the punching operation of all of the units simultaneously. As illustrated in Fig. 1, a scale 98 may be provided on the front edge of the base member for convenience in adjusting the individual units and each unit may be provided with a scored line 100 in alignment with the punch member 16 for use in cooperation with the scale. When the device is used for punching holes in a sheet of paper to be prepared for insertion in a three-ring loose leaf binder, the punch units 12 may be adjusted to the proper spacing, as illustrated in Fig. 1.

Referring now to Figs. 3 and 9, the individual punch units may be adjusted to punch out two holes in the desired spaced relation by moving one of the three units to the extreme left-hand end of the base member in which position it may be used as an end stop as shown in Fig. 8 the remaining two units being adjusted in proper spaced relation. Fig. 9 shows a further expedient for adjusting the units whereby but one hole may be punched in a sheet by moving two of the individual punch units to the extreme right-hand end of the device the remaining unit being adjusted as desired. When two holes in different spaced relation are desired, another of the units may be moved into operative position as indicated by the unit shown in dotted lines in Fig. 9.

As illustrated in Figs. 1 and 4, the present construction of punch enables plastic covering parts to be used for decorative purposes and for comfort in handling the punch. As herein shown, the base member 10 may be provided with a plastic covering member 102 which may fit snugly over the base member being hooked around the forward portion thereof, and may be secured to the end walls of the base member by rivets 104. The presser bar 14 may also be provided with a plastic covering member 106 snugly fitted thereover and which may be hooked over the upper end thereof and secured to the arms 78 of the presser bar 14 by the pivot pins 80 by which the bar is pivotally connected to the base member 10.

As herein illustrated, the lower portion of each punch unit 12 forms a receptacle 108 open at one and in which the punched out portions of the paper are received. In order to confine the punched out portions within the units and also to improve the appearance of the device, a stationary curved shield member 110 extending the full length of the device may be provided which may and preferably will be detachably connected to the base member 10 and arranged to cover the open portion of the units in any of the different positions of adjustment of the latter. The shield may be detachably retained in assembled position by a curved spring 112 secured to the base member, and arranged to fit into an opening 114 formed in the shield. As shown in Fig. 4, the rear wall of the plastic cover 102 may be provided with a cut out 116 to permit the spring to be moved out of the way to remove the shield when it is desired to dispose of the punched out portions.

From the foregoing description it will be observed that the punch units of the present multi-hole punch may be adjusted to punch one or more holes in the paper sheet or sheets to locate the holes in predetermined spaced relation to one an-

other and at predetermined distances from an edge of the sheets, and that the construction is such as to provide unobstructed vision and accessibility to facilitate adjustment of the punch units and insertion of the paper to be punched.

The present multi-hole punch may be made of relatively light weight sheet metal which may be stamped out to the required shape thereby enabling the punch to be economically manufactured. Although light in weight, the parts are designed to provide maximum rigidity and structural strength.

While the preferred embodiment of the invention has been thus described, it will be understood that the invention may be embodied in other forms within the scope of the following claims.

Having thus described the invention, what is claimed is:

1. A multi-hole paper punch comprising an elongated base member, a guide rod carried by said base member, a plurality of individual punch units adjustably supported in said base and slidably mounted on said elongated rod, means for frictionally retaining the units in their adjusted position including a yieldable member carried by each of said punch units and in frictional engagement with said rod, and an actuating member pivotally mounted in said base and cooperating with said punch units to perform the punching operation in the different adjusted positions of said units, said yieldable member comprising a U-shaped spring having an opening in the upright legs thereof through which the rod may pass and having a reversely curved extension from one leg bearing against the rod.

2. A multi-hole paper punch comprising an elongated base member, a plurality of individual punch units adjustably supported in said base member, each of said units including a punch member, a punch plate having a hole with which said punch member is adapted to cooperate, an individual presser arm for each punch unit directly connected to its respective punch member, and an elongated presser bar pivotally mounted on said base and operatively connected to said individual presser arms to perform the punching operation.

3. A multi-hole paper punch comprising an elongated base member, a plurality of individual punch units adjustably supported for lengthwise movement in said base member, each of said units including a punch member, a punch plate having a hole with which said punch member is adapted to cooperate, an individual pivotally mounted presser arm for each punch unit, a pin and slot connection between said arms and their respective punch members providing a direct connection therebetween, a coil spring bearing against said arms for urging the latter and said punch members into an upraised position, and an elongated presser bar pivotally mounted in said base arranged to cooperate with said individual punch units to permit adjustment of the latter lengthwise of the bar and to effect positive movement of said punch members upon rocking movement of said bar in either direction.

4. A multi-hole paper punch comprising a base member, a plurality of individual punch units mounted on said base to be capable of adjustment longitudinally thereof, and an actuating member mounted on said base for operating all of said individual punch units in their different adjusted positions, the lower portion of each individual punch unit forming a receptacle open 75 at one end for receiving the punched out por-

tions of the paper, and a shield detachably connected to said base and arranged to cover the open end of said receptacles in the different positions of adjustment of said punch units.

5. A multi-hole paper punch comprising a base member, a plurality of individual punch units mounted on said base to be capable of adjustment longitudinally thereof, and an actuating member mounted on said base for operating all of said individual punch units in their different adjusted positions, a plastic cover snugly fitted over and detachably secured to said base member, and a plastic cover snugly fitted over and detachably secured to said actuating member.

6. A paper punch unit comprising a punch member, a unitary bracket made from one sheet of metal bent to form a structure substantially rectangular in cross section for supporting said punch member for vertical movement, a punch plate formed integrally with said bracket and supported across the upper edges of the vertical side walls of said bracket and having an opening therein for cooperation with said punch member, a presser arm pivotally carried by extensions from the side walls of said bracket, and connections between said arm and said punch member for effecting the punching operation.

7. A paper punch unit comprising a punch member, a unitary supporting bracket made from one sheet of metal bent to form a structure substantially rectangular in cross section to provide an upper wall, side walls and a bottom wall, said upper wall having a portion bent downwardly and inwardly to form an intermediate wall, said upper wall and intermediate wall having aligned openings therein for supporting said punch member for vertical movement, said side walls having a paper receiving slot formed therein, a punch plate having an opening therein for cooperation with said punch member, said punch plate being disposed in the lower portion of said slot and extending across and bearing against the edges of said side walls whereby to form a firm and rigid support for said plate, said plate being bent and extended under the bottom wall of said bracket, said plate forming the upper wall of a chamber for the collection of punched out portions and a presser arm pivotally carried in extended portions of said side walls and operatively connected to said punch member to perform the punching operation.

8. A multi-hole paper punch comprising an elongated base member, a plurality of individual punch units adjustably supported in said base member for movement lengthwise thereof, each of said units including a punch member, a punch plate having an opening for cooperation with said punch member, an individual pivotally mounted presser arm carried by each unit and directly connected to its respective punch member, and an elongated presser bar pivotally mounted in said base having its outer end shaped

to form an elongated socket adapted to receive and retain the outer ends of said presser arms and to permit adjustable movement thereof lengthwise of the socket, said socket connection also being capable of effecting positive movement of said arms upon rocking movement of said presser bar in either direction.

9. A multi-hole paper punch comprising an elongated base member, a plurality of individual punch units adjustably supported in said base member for movement lengthwise thereof, each of said units including a punch member, a punch plate having an opening for cooperation with said punch member, an individual pivotally mounted presser arm carried by each unit and provided with a slotted portion, a pin carried by said punch member and engageable with said slot to provide a direct connection between the arm and the punch member and arranged to permit relative movement between the punch and the arm during the punching operation, and an elongated presser bar pivotally mounted in said base having its outer end shaped to form an elongated socket adapted to slidably receive the outer ends of said arms and adapted to effect movement with the bar whereby to permit positive lifting of said punch member by upward rocking of said bar in the event that the punch member becomes jammed in its punching position.

10. A multi-hole paper punch comprising an elongated base member having upwardly extended end walls, one of said walls serving as an end stop for one edge of the sheet to be punched, the other being slotted to permit a sheet longer than the base to be inserted, the end of said slot serving as a depth gauge, a plurality of individual punch units adjustably supported for lengthwise movement in said base, each of said units having a slot at least equal to the depth gauge slot in said one end wall, an individual pivotally mounted presser arm carried by each unit, and an elongated presser bar hingedly secured to said end walls having its pivot in alignment with the pivots of said presser arms, said presser bar being operatively connected to said arms for rocking movement therewith in either direction.
